UNITED STATES PATENT OFFICE.

FREDERIK G. WHITTINGTON, OF EVANSTON, ILLINOIS, ASSIGNOR TO STEWART-WARNER SPEEDOMETER CORPORATION, OF CHICAGO, ILLINOIS, A CORPORATION OF VIRGINIA.

DESIGN FOR A STOP-SIGNAL LENS.

Application filed June 21, 1922. Serial No. 2,756. Term of patent 14 years.

To all whom it may concern:

Be it known that I, FREDERIK G. WHITTINGTON, a citizen of the United States, residing in Evanston, in the county of Cook and the State of Illinois, have invented a new, original, and ornamental Design for a Stop-Signal Lens, of which the following is a specification, reference being had to the accompanying drawing, forming a part thereof.

The drawing is a face view of a stop signal lens embodying my new design.

I claim:—

The ornamental design for a stop signal lens substantially as shown.

In testimony whereof, I have hereunto set my hand at Chicago, Illinois, this 16th day of June, 1922.

FREDERIK G. WHITTINGTON.
